[57] CLAIM

The ornamental design for a picnic basket, as shown and described.

DESCRIPTION

FIG. 1 is a front perspective view of a picnic basket with the lid in an open position showing my new design, the opposite side is a mirror image of the side shown; FIG. 2 is a front perspective view thereof with the lid in a closed position;

FIG. 3 is a top plan view thereof;

FIG. 4 is a bottom plan view thereof;

FIG. 5 is a side elevational view thereof, the opposite side is a mirror image of the side shown;

FIG. 6 is a front elevational view thereof; the rear elevational view being a mirror image; and,

FIG. 7 is a front perspective view of a second embodiment of a picnic basket showing my new design, the rear and other side of FIG. 7 is like the front and side shown.

FIG. 1

FIG. 4
